By Riley, Robinson & Love

ATTORNEY'S.

UNITED STATES PATENT OFFICE.

FREDERICK M. MILLER, OF DEERFIELD, NEW YORK.

DESIGN FOR A SUBLIMATORY.

SPECIFICATION forming part of **Design No. 26,976**, dated **April 27, 1897**.

Application filed October 5, 1896. Serial No. 607,964. Term of patent 3½ years.

To all whom it may concern:

Be it known that I, FREDERICK M. MILLER, a citizen of the United States, and a resident of Deerfield, in the county of Oneida and State of New York, have invented and produced a new and original Design for a Sublimator Instrument, of which the following is a specification, reference being had to the accompanying drawings, showing the same.

In the drawings, Figure 1 shows a perspective view of the instrument, and Fig. 2 shows a plain side elevation.

The novelty of my design is in the general

form or shape of the instrument, as shown—that is, having a bell-shaped body, the upwardly-inclined tapering spout, and the handle, as shown.

What I claim is—

The design for a sublimator instrument herein shown and described.

In witness whereof I have affixed my signature in presence of two witnesses.

FREDERICK M. MILLER.

Witnesses:

PHEBE A. TANNER,
D. H. COLEGROVE.
